Primary Examiner—A. Hugo Word**Assistant Examiner—Doris Clark****Attorney, Agent, or Firm—Kent A. Herink; Brian J. Laurenzo****[57] CLAIM**

The ornamental design for a structural beam for concrete form systems, as shown and described.

DESCRIPTION

FIG. 1 is a front perspective view of a structural beam for concrete form systems showing my new design;

FIG. 2 is a side elevational view thereof;

FIG. 3 is a front elevational view thereof;

FIG. 4 is a top plan view thereof; and,

FIG. 5 is a cross-sectional view taken along line 5—5 of FIG. 3.

FIG.2

1

**REEXAMINATION CERTIFICATE
ISSUED UNDER 35 U.S.C. 307**

THE PATENT IS HEREBY AMENDED AS
INDICATED BELOW.

2

AS A RESULT OF REEXAMINATION, IT HAS BEEN
DETERMINED THAT:
The single claim is cancelled.
